DESIGN FOR AN ALPHABET OR SIMILAR ARTICLE

Ole H. Sam, Stillwater, Minn.

Application August 9, 1938, Serial No. 79,205

Term of patent 7 years

To all whom it may concern:

Be it known that I, Ole H. Sam, a citizen of the United States, residing at Stillwater, in the county of Washington and State of Minnesota, have invented a new, original, and ornamental Design for an Alphabet or Similar Article, of which the following is a specification, reference being had to the accompanying drawing, forming part thereof.

The figure of the drawing is a face view of an alphabet or similar article showing my design.

The letters of the alphabet or similar article have no appreciable thickness.

I claim:

The ornamental design for an alphabet or similar article, as shown and described.

OLE H. SAM.
